CLAIM

The ornamental design for a blender attachment, substantially as shown and described.

DESCRIPTION

FIG. 1 is a top, front, and right side perspective view of a blender attachment showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, rear, and left side perspective view thereof.

Features shown in broken lines in the drawings form no part of the claimed design.

1 Claim, 8 Drawing Sheets
